(57) **CLAIM**

The ornamental design for a robotic bartender and bar, as shown.

DESCRIPTION

FIG. 1 is a perspective view of a robotic bartender and bar illustrating our new design;

FIG. 2 is a front view of the design of FIG. 1;

FIG. 3 is a right side view of the design of FIG. 1;

FIG. 4 is a left side view of the design of FIG. 1;

FIG. 5 is a rear view of the design in FIG. 1; and,

FIG. 6 is a top plan view of the design of FIG. 1.
